UNITED STATES PATENT OFFICE

HENRY SHEPLEY BOOTH, OF MANCHESTER, ENGLAND, ASSIGNEE, BY MESNE ASSIGNMENTS, TO UNDERWOOD COMPUTING MACHINE COMPANY, OF NEW YORK, N. Y., A CORPORATION OF NEW YORK.

CALCULATING MACHINE.

1,227,033.

Specification of Letters Patent.

Patented May 22, 1917.

Application filed May 2, 1912. Serial No. 694,742.

To all whom it may concern:

Be it known that I, HENRY SHEPLEY BOOTH, a British subject, residing at Manchester, county of Lancaster, England, have invented certain new and useful Improvements in Calculating-Machines, of which the following is a specification.

This invention relates to machines for adding and subtracting adapted to be fitted 10 to type-writing machines wherein the action or depression of a numeral key operates the calculating mechanism and also projects a type carrying bar against an inked ribbon and platen to print and record the item.

15 The object of the invention is to provide means to print a special mark or character upon the paper only when all the totalizer wheels are at zero, to prevent such mark or character being printed at any other position of the wheels and to print on the paper a second mark or character adjacent to any numeral printed thereon which has been subtracted.

The invention will be described with reference to the accompanying drawings in 25 which sufficient of a typewriting machine is shown to illustrate the invention.

Figure 1. is a front elevation.

Fig. 2. is a side elevation.

30 Fig. 3. is an elevation of the tens wheels, the arms associated therewith, and the swinging bar connected with said arms, the view being taken from the back of the machine.

35 Fig. 4. is a front elevation of the auxiliary type bar and its operating mechanism.

Fig. 5. is a plan of same.

Fig. 6. is a side elevation of same.

The type-writing machine is of any ordinary or known construction as is also the calculating mechanism coupled to the numeral keys of the typewriter.

The key K is one of the ordinary numeral keys and the key K' is a key with a marking such as two horizontal lines =, by printing which several times a double ruling may be effected. This key may have any other marking to be printed to indicate the end of a calculation.

50 I provide a locking mechanism operated by the totalizer wheels to lock the key K'

and prevent it being operated to print the double ruling except when all the totalizer wheels are at zero. When therefore a total is to be printed the machine should be set to 55 subtract, and the subtraction thereof, as it is being printed, will return all the wheels to zero. This will unlock the key K', and the ability to operate it and print the double ruling (or other marking) will prove that 60 the transcription of the total is correct. If an error has been made in transcribing the total, the key K' will not be unlocked and cannot be operated.

The drum or boss w of each of the totalizer wheels W⁵ is provided with a V notch cut therein to receive a corresponding V piece on the end of an arm or lever P' which is in position to engage therewith when the wheel indicates zero.

70 The arms P'—one for each set of wheels—are mounted upon a spindle S' carried across the back of the totalizer and journaled in the frame of the machine. On the end of the spindle S' a swinging rod R is fitted, 75 said rod carrying at its lower end a pin r, and to the key K' a lever L is connected by the link k. The lever L is at its free end formed with a hook to engage the pin r of the swinging rod R. A similar arm P², also 80 on the spindle S', engages a V notch on the pence wheel W⁶. When all the wheels W⁵ and W⁶ are at zero and the arms are in the several notches, the swinging rod R hangs perpendicular, the pin r is free of the hooked 85 end of the lever L, and the key K' is free to be operated and print the double rule or distinctive mark thereon. Should however any one of the wheels W⁵ or W⁶ not be at zero, the swinging arm R is moved into engagement with the hooked end of the lever L, thus locking the key K' and preventing it from being operated. For tens of shillings, the wheel W⁵ has five V notches and the pence wheel W⁶ is fitted with a V notch to 90 correspond with zero on the pence indicator, the arm P² being fitted at a different angle on the spindle S'.

An auxiliary type bar T is mounted on the type guide T' in such a manner as to be capable of being moved to and fro horizontally, to bring it into and out of the path of

the ordinary type bars. The type bar T is fitted with a character, such as a dot or stroke, which is printed when struck by the type bar along with the numeral thereon, to indicate that the numeral then printed has been subtracted. The type bar T is elastic or jointed, being made of preferably spring steel. It is coupled to a crank lever t and operated by a cam A through a lever a and link a'. The link a' is slotted to allow the platen to be lowered and throw the auxiliary type bar out of action except when the platen is in position to print numerals.

The cam A is mounted on the spindle B by which the totalizer is changed from addition to subtraction. The rotation or turning movement which effects this change rotates the cam A and moves the auxiliary type bar T into the path of the numeral type bars, and any one of these, on being operated, will strike the bar T and force or bend it against the ink ribbon and paper and simultaneously print its distinguishing mark with the numeral, to indicate that the number in question has been subtracted by the calculating mechanism.

The auxiliary type bar may be moved into position to print when the mechanism is set to add, if so desired, by altering the position of the cam A, but at present I prefer to use it to indicate subtraction.

I do not claim herein broadly the combination of a totalizer, means for printing a characteristic mark, mechanism for locking said printing means, and means rendering said locking mechanism ineffective when said totalizer stands at zero; nor do I claim herein broadly the combination of a totalizer, a key for printing a characteristic mark, mechanism for locking said key, and means for rendering said locking mechanism ineffective when said totalizer stands at zero; said combinations being broadly covered by the application of Frederick A. Hart, Serial No. 662,873, filed November 28, 1911.

What I claim as my invention and desire to protect by Letters Patent is:—

1. In a calculating machine adapted as a type-writing machine, the combination, with the numeral type bars and the totalizer, of an auxiliary type bar to print a distinctive mark simultaneously with the numeral, and means for automatically moving the auxiliary type bar into the path of the numeral type bars when the totalizer is set for calculating operation of a given character, substantially as described.

2. In a calculating machine adapted as a type-writing machine, the combination, with a totalizer, of apparatus to print a distinctive mark when the totalizer is at zero, and to print a distinctive mark simultaneously with the numeral when the mechanism is set

to either subtract or to add, substantially as described and shown.

3. In a computing machine, the combination with computing mechanism, of a state-indicating printing sign, numeral printing keys for printing the number computed and for controlling said computing mechanism, means to set said state-indicating sign to printing position and to change the control of the computing mechanism by said keys to print the totals standing on the computing mechanism and thereby clear the same, a clearance printing sign, and means for causing the positioned state-indicating sign to print by the action of said numeral keys as an incident to the printing of a total thereby, said keys also acting to enable said clearance sign to print at the conclusion of the printing of the total and the clearing of the computing mechanism.

4. In a computing machine, the combination with computing mechanism, of numeral printing keys for controlling said computing mechanism, a state-indicating sign, a clearance sign, a lock for said clearance sign normally effective to prevent printing by said clearance sign, means for positioning said state-indicating sign to printing position and for changing the control of said computing mechanism by said keys to cause a change of state of said computing mechanism, and means to cause said positioned state-indicating sign to print, as said numeral keys are operated to print the digits corresponding to the total standing on said computing mechanism and to clear said computing mechanism, said numeral printing keys while thus printing the total acting through the medium of said computing mechanism to release said lock to enable said clearance sign to be printed.

5. In a combined typewriting and computing machine having a computing mechanism, numeral types, and numeral keys controlling said numeral types to print the numbers run up on said computing mechanism; the combination of a special printing type, the printing action of said type being under the joint control of the computing mechanism and one of said numeral keys.

6. In a combined typewriting and computing machine having a computing mechanism, numeral keys controlling said mechanism, and a state-controlling mechanism for determining the addition or subtraction condition of said computing mechanism; the combination of a special printing type, the printing action of said type being under the joint control of any one of said numeral keys and said state controlling mechanism.

7. In a combined typewriting and computing machine having a computing mechanism, numeral keys controlling said mechanism, and a state-controlling mechanism for

- 5 determining the addition or subtraction condition of said computing mechanism; the combination of a special printing type, the printing action of said type being under the joint control of a numeral key and said state controlling mechanism.
- 6 8. In a combined typewriting and computing machine having numeral types and computing mechanism, numeral keys controlling said numeral types to print the numbers carried into the computing mechanism, and a state-controlling mechanism for determining the addition or subtraction condition of said computing mechanism; the combination with a special printing type and means under control of the state-controlling mechanism for interposing said special type into the path of movement of a numeral type, whereby said special type is operated to print on the operation of said numeral type.
- 10 9. In a combined typewriting and computing machine having numeral types and computing mechanism, numeral keys controlling said numeral types to print the numbers carried into the computing mechanism, and a state-controlling mechanism for determining the addition or subtraction condition of said computing mechanism; the combination with a special printing type and means under control of the state-controlling mechanism for interposing said special type into the path of movement of any one of said numeral types, whereby said special type is operated to print on the operation of any one of said numeral types.
- 15 10. In a combined typewriting and computing machine having computing mechanism, numeral types for printing digit by digit the number computed by said computing mechanism; the combination with a special printing type to indicate the state of the computing mechanism as to addition or subtraction, said type being actuated to print as incident to the printing of the number digit by digit by said numeral types.
- 20 11. In a computing machine the combination with numeral keys, computing mechanism controlled by said numeral keys, and digit printing mechanism, of a special printing sign and means to enable said numeral keys to cause said special printing sign to print.
- 25 12. In a combined typewriting and computing machine having computing mechanism, numeral types for printing the number computed by the computing mechanism; the combination with a special type arranged in proximity to the numeral types and operating to print as an incident to the printing of any one of said numeral types to indicate the state of the computing mechanism as to addition or subtraction.
- 30 13. In a combined typewriting and computing machine having computing mecha-
- nism, numeral types for printing the number computed by the computing mechanism; the combination with a special type to indicate the state of the computing mechanism as to addition or subtraction, and means for interposing said special type into the path of movement of said numeral types, to cause said special type to print as an incident to the printing of said numeral types to indicate the state of the computing mechanism as to addition or subtraction.
- 35 14. In a computing machine, the combination with computing mechanism, of numeral printing keys for controlling said computing mechanism and for printing the digits computed, and a special printing sign for showing the state as to addition or subtraction of said computing mechanism, the printing by said special printing sign being caused by said numeral keys.
- 40 15. In a computing machine, the combination with computing mechanism, of numeral printing keys for controlling said computing mechanism and printing the digits computed, a special printing sign, and means for causing said special printing sign to be printed as said numeral printing keys print the digits of a number to be computed.
- 45 16. In a combined typewriting and computing machine, the combination with typewriting mechanism including a platen and printing mechanism relatively shiftable to control the printing of different characters on said platen, of computing mechanism, means for determining the state of said computing mechanism, a special printing sign, and means dependent upon the position of said state-determining means and the relative position of said printing mechanism and platen for positioning said sign.
- 50 17. In a combined typewriting and computing machine, the combination with typewriting mechanism including a platen and printing mechanism relatively shiftable to control the printing of different characters on said platen, of computing mechanism, means for determining the state of said computing mechanism, a special printing sign, numeral keys for controlling said computing mechanism and also the printing of said sign, and means dependent upon the position of said state-determining means and the relative position of said printing mechanism and platen for positioning said sign to be actuated by said numeral keys to print.
- 55 18. In a combined typewriting and computing machine, the combination with typewriting mechanism including a platen and printing mechanism relatively shiftable to control the printing of different characters on said platen, of computing mechanism, means for determining the state of said computing mechanism, a special printing sign, numeral printing keys for printing digit by

digit the computed number, and means dependent upon the position of said state-determining means and the relative position of said printing mechanism and platen for 5 positioning said sign to be actuated by said numeral printing keys as they print digit by digit.

In testimony whereof I have hereunto set my hand in presence of two subscribing witnesses.
